UNITED STATES PATENT OFFICE.

ANTHON MORRIS STROM, OF CHICAGO, ILLINOIS, ASSIGNOR TO THE TOY TINKERS, INC., OF EVANSTON, ILLINOIS, A CORPORATION OF ILLINOIS.

DESIGN FOR A TOY SURF BOAT.

Application filed October 20, 1924. Serial No. 11,129. Term of patent 14 years.

To all whom it may concern:

Be it known that I, ANTHON MORRIS STROM, a citizen of the United States, residing at Chicago, in the county of Cook and State of Illinois, have invented a new, original, and ornamental Design for a Toy Surf Boat, of which the following is a specification, reference being had to the accompanying drawing, forming part thereof.

The drawing is a perspective view of a toy surf boat, showing my new design.

I claim:

The ornamental design for a toy surf boat, as shown.

ANTHON MORRIS STROM.
